UNITED STATES PATENT OFFICE.

CLIFFORD S. GOBY, OF CLEVELAND, OHIO, ASSIGNOR, BY MESNE ASSIGNMENTS, TO THE ROCKEFELLER MOTOR COMPANY, OF CLEVELAND, OHIO, A CORPORATION OF OHIO.

INTERNAL-COMBUSTION ENGINE.

1,208,308.

Specification of Letters Patent. Patented Dec. 12, 1916.

Application filed June 24, 1910. Serial No. 568,612.

To all whom it may concern:

Be it known that I, CLIFFORD S. GOBY, a citizen of the United States, residing at Cleveland, in the county of Cuyahoga and State of Ohio, have invented a certain new and useful Improvement in Internal-Combustion Engines, of which the following is a full, clear, and exact description, reference being had to the accompanying drawings.

This invention relates to internal combustion engines, the embodiment shown herein being of the four-cycle type, although certain features of construction of my invention are applicable to the two-cycle type of engine as well as to the four-cycle type.

The invention disclosed herein relates more particularly to the type of internal combustion engine shown in my Patent No. 1,100,656, issued June 16, 1914, and to the valve construction which is illustrated, described and claimed in my application 795,819, filed Oct. 18, 1913, a division of the aforesaid patent.

25 The invention herein consists in certain combinations and arrangements of parts of the valves and the lay-shaft chamber which are not claimed in the aforesaid application.

Generally speaking, the invention may be 30 further defined as consisting of the combinations of elements embodied in the claims hereto annexed and illustrated in the drawings forming part hereof, wherein—

Figure 1 represents a view, partly in plan 35 and partly in section, of a four cylinder engine constructed in accordance with my invention; Fig. 2 represents a view, partly in side elevation and partly in vertical section, of the engine shown in the preceding figure; Fig. 3 represents a front elevation of the engine shown in the preceding views, certain 40 parts being illustrated in section; Fig. 4 represents a detail in elevation of the valve and the operating means therefor; Fig. 5 represents a side elevation of the inner guide member for the valve proper, and Fig. 6 a detail, partly in section and partly in elevation, of the engine and "lay" shaft, with a driving connection therebetween.

50 The engine frame consists generally of a base section 1 and an upper section 2, said sections being formed as separate castings, the upper section being provided at its base with a flange 3 adapted to rest on top of the base section 1. The base section has formed

therewithin a crank chamber for the main shaft and its cranks and a chamber for the lay shaft and its cranks, said chambers being preferably in free communication with each other.

60 The upper section 2 forms, with a cover section, a water jacket for the cylinders and for the inlet and exhaust valves, completely surrounding the cylinder heads and the valves, particularly the portions of the said 65 cylinders and valves which are subjected to the highest temperatures. Furthermore, the construction of water jacket disclosed possesses structural advantages, enabling it to be cast with a minimum of coring. Within 70 the section 2 are mounted the cylinders 4. Each cylinder is cast with the cover section 5, the cover being integral with all of the cylinders, and the cylinders, together with the corresponding cover section, are secured 75 in place by means of rings 6 threaded onto the exterior of the lower end of each cylinder and engaging the base of the upper section 2, the lower end of such section being contracted, as shown at 2^a, to form a bearing 80 for the upper edge of the rings and a close joint with the cylinders.

The cover section 5 extends the full length and width of the engine and is provided with suitable openings in the top for the reception of cover plates 7, which may be conveniently and removably anchored by means 85 of bolts 8, having each a cross head 9 at its lower end adapted to extend across the bore of the valve chamber beneath said cover and engage a flange 10. The covers are secured in place by means of nuts 11 on the outer or upper ends of the bolts.

90 Cast with each cylinder 4 but spaced therefrom is a pair of valve casings, each being 95 in the form of a sleeve 12, each sleeve being provided, about midway of its length, with a series of segmental ports 13, extending partially therearound and communicating with a duct 14 carried by and merging with 100 the head of each cylinder 4. This sleeve depends also from the cover section 5, being preferably cast with the head and with the walls of the duct 14, and is provided with a ring 15 threaded onto its lower end and 105 abutting against a wall 16 carried by the upper section 2, said wall extending entirely around the sleeve and forming the top of the chamber which contains the lay shaft. In order to prevent leakage, a packing ring 110

17 is inserted in a suitable recess between the ring 15 and the wall 16.

Within each casing 12 there is mounted a tubular slide valve 18, said valve being 5 cylindrical and being connected at its lower end by a connecting rod 19 with a crank 20, projecting from the lay shaft 21. The slide valve 18 is provided, about midway of its length, with a series of segmental ports 22 10 adapted to communicate with the corresponding ports 13 in the outer sleeve or valve casing 12. Within the slide valve 18 there is mounted a liner or bushing 23, said liner or bushing being anchored within the sliding 15 valve by an arm 24 from any convenient part of the upper casing section. As shown more particularly in Fig. 3, adjacent liners or bushings may be supported from a common pin 25 extending through a web 26 carried by the upper casing section 2. The liner or bushing 23 has a transverse partition 27 therein, about midway of its height, and is provided above such partition with a series of segmental ports 28 adapted to 20 register with the ports 22 and 13. The liner or bushing 23 and the casing 12 form an annular valve seat for the cylindrical slide valve 18 and, to prevent leakage between the sleeve 12 and the slide valve 18, the latter is provided with packing rings 29 and 30 25 located respectively above and below the segmental ports 22 and adapted to bear against the sleeve 12.

It will be observed that each cylinder is 30 provided with a pair of similarly constructed valves, each valve comprising a sliding sleeve with an inner and an outer sleeve or bushing between which it moves. One of these valves is for the supply of the combustible mixture to the cylinder and one is 35 for the exhaust of the gases of combustion from the cylinder. In the arrangement shown herein, the inner of the two valves of each of the outermost cylinders of the series 40 is an inlet valve and the outer valve of each of the middle pair of cylinders is an inlet valve, the inlet valves for an end cylinder and the next adjacent cylinder being connected with a common inlet branch pipe 31, 45 the branch pipes merging into a common supply pipe 32. The outlet valves are connected by suitable pipe sections and branches 33 with a common outlet pipe 34. As will appear from Fig. 1, the upper ends 50 of the valves for each cylinder are separated by a partition 35, whereby the inlet and exhaust gases are maintained separate, the arrangement of these parts being shown in connection with the second cylinder.

55 The upper casing section 2 and the cover section 5 provide a water jacket for the cylinders and valves. As will appear from Figs. 1 and 2, this water jacket entirely surrounds the upper portion of each cylinder, including the connection 36 which pro-

jects laterally therefrom and which forms a combined fuel inlet and exhaust outlet for each cylinder. The water jacket surrounds the inlet and outlet of each cylinder and the outer valve sleeves or casings for substantially the entire length of the latter, the arrangement securing a very efficient cooling of the parts which are apt to be raised to the highest temperature in the operation of the engine.

In the lower portion of the casing is mounted the main shaft 37, said shaft being provided with cranks, one for each cylinder, the cranks being connected by the usual connecting rods 38 with their respective pistons 39. The pistons will be of usual construction and the adjacent cranks will project from the main shaft at an angle of 180 degrees with respect to each other. One end of the shaft is provided with a fly wheel 40 and the opposite end is shown as provided with a spiral gear 41 meshing with a similar spiral gear 42 on an intermediate shaft 43 which carries at its opposite end a spiral gear 44 meshing with a similar gear 45 on the lay shaft 21. The shaft 43 is provided with anti-friction bearings 46. As will appear more particularly from Fig. 5, the parts are so arranged that the shaft 21 will be driven at a slower rate of speed than the main shaft 37, the reduction being four to one. With this ratio of reduction, the ports in the inlet valve will be brought into register with the ports in the surrounding casing only during alternate reciprocations of the piston and, for the same reason, the ports in the exhaust valve will be brought into register with the ports in the surrounding casing only during alternate reciprocations of the piston, while the manner of connecting the inlet and outlet valves to the lay shaft will cause the ports of the two valves to register with their respective casing ports during successive reciprocations of the piston. Furthermore, by the use of this ratio of reduction and the location of the port or ports within their respective valves, each valve will have its port or ports opened and closed by a continuous movement of the valve in one direction; also the port or ports of each valve will open and close by movements which are successively in opposite directions and these movements will occur during corresponding cycles of the piston.

100 By reference to Fig. 2, it will be seen that the center of the lay shaft 21 is offset from the axis of the valve sleeves. This offset arrangement is necessary in order to allow for the proper timing adjustment of the valves, whereby the ports in the valves may register with the ports in their surrounding casings or sleeves at the proper position of the pistons in the cylinders 4. As previously stated, two similar valves are provided with each cylinder, namely; an inlet valve and

an exhaust valve. With the four-cylinder engine shown herein, four inlet and four exhaust valves will be provided. Each valve is connected with the lay shaft 21 by a connecting rod 19 and a crank 20, and the cranks are so arranged that each will be forty-five degrees distant from its adjacent crank. As will appear from Fig. 2, each cylinder will be provided with the usual 10 electrical igniting device 49 which may be carried by a bushing 50 threaded into the top of the cylinder. The casing will be provided with suitable removable plates 51, 52, 53 and 54 for purposes of inspection, repair, 15 etc. of the parts within the casing.

Among the advantages of the invention disclosed herein are:—The construction of the water jacket, which not only secures economy of production (the jacket consisting 20 merely of the upper section 2 and the cover 5 therefor) but also simplicity and convenience in assembling; also the water jacket is so constructed that the parts which are subjected to the greatest heat are entirely surrounded with water. The valve construction which, while securing maximum efficiency and avoiding the necessity for cam shafts and puppet valves, avoids the necessity for careful machining. The 25 suspending of the inner cylinder or bushing in the manner shown secures an uninterrupted supply of fluid to the inlet valve and the construction provides at all times an ample supply of fluid to and from the cylinder head through the ports. This ample supply of fluid to and from the cylinders is further insured by the relatively slow movement of the valves, following from the four-to-one reduction between the engine 30 shaft and the lay shaft. Furthermore, the particular construction of the valve proper prevents leakage from the supply into the cylinder and vice versa. The extension of the inner liner or bushing 23 downwardly 35 below the partition 27 prevents leakage into the crank case, while its extension above the ports 28 prevents leakage when the valve sleeve is elevated. The pivotal support for the liners or bushings, afforded by the pins 40 25 and arms 24, enables these parts to "float" within their respective valves and to adjust themselves to bring their axes into coincidence with the axes of their respective valves, whereby binding is eliminated. Furthermore, the abutments or partitions 27 deflect the gases which enter the liner sleeves or bushings (either from the inlet supply 45 or through the ports 28, from the cylinder) and prevent such gases from entering the lay-shaft casing and the crank casing.

A still further advantage, which arises from the particular construction of the upper portion of the valve, is the provision of a free, full, and uninterrupted supply 50 of fluid to and from the inner cylinder or

casing of the valve. The provision of the channel 55 surrounding the portion of each valve sleeve remote from the cylinder head provides a balanced construction which minimizes the tendency of the valve sleeve to bind and causes the sleeve to wear evenly in its seat.

A further and very important point of advantage resides in the fact that there is no loss of compression in the cylinder due 75 to the movement of the valve sleeve and no appreciable pumping action on the fuel supply.

The placing of the two crank cases in communication or the making of the two 80 crank cases substantially in one allows both sets of shaft connections to be oiled by the "splash" system.

The arrangement of the valve ports and the manner of operating the valves enables 85 one to readily and conveniently inspect any of the valves and to quickly and easily remove and replace any valve or valves should occasion require.

Having thus described my invention, what I claim is:—

1. In an internal combustion engine, the combination of a plurality of cylinders, a cylindrical valve chamber for each cylinder having a port intermediate of its ends 95 communicating with its cylinder and having an open bottom and extending substantially parallel with each cylinder, a plate through which the bottoms of said valve chambers extend, a chamber beneath said plate, a shaft in the latter chamber, a tubular valve slidably mounted in each valve chamber and having a port intermediate of its ends adapted to register with the corresponding port of its valve chamber, means connecting 100 said valves with said shafts, an abutment in each valve extending across the bore thereof beneath the port in said valve, and a ring threaded in the lower end of each valve chamber and adapted to bear against the 110 lower surface of the plate.

2. In an internal combustion engine, the combination of a plurality of cylinders, a valve casing extending substantially parallel with each cylinder and having a port 115 communicating with its cylinder, a plate through which the bottoms of said casings extend, a chamber beneath said plate, a shaft in said chamber, a tubular valve slidably mounted in each of said valve casings 120 and each having a port adapted to register with its valve casing port, means connecting said valves with said shaft, and an abutment in each valve extending across the interior thereof and arranged to prevent the 125 gases flowing through its port from passing into the chamber beneath the plate.

3. In an internal combustion engine, the combination of a cylinder, a valve casing 130 separate from the cylinder and having a

- port adapted to communicate with the cylinder, a tubular valve longitudinally movable in said casing and having a port in its wall adapted to register with the casing 5 port, an abutment in said valve at one side of the port thereof, and a pivotal support for said abutment.
4. In an internal combustion engine, the combination of a cylinder, a valve casing 10 separate from the cylinder and having a port adapted to communicate with the cylinder, a tubular valve longitudinally movable in said casing and having a port in its wall adapted to register with the casing 15 port, a tubular liner within the valve and having a port adapted to register with the former ports and provided with an abutment at one side of its port, and a pivotal support for said liner.
5. In an internal combustion engine, the combination of a cylinder, a valve casing 20 separate from the cylinder and having a port adapted to communicate with the cylinder, a tubular valve longitudinally movable in said casing and having a port in its wall adapted to register with the casing 25 port, a tubular liner within the valve and having a port adapted to register with the former ports and provided with an abutment 30 at one side of its port, an arm connected to said liner, and means pivotally anchoring said arm.
6. In an internal combustion engine, the combination of a cylinder, a valve casing 35 adjacent thereto and having a port adapted to communicate therewith, a sliding sleeve valve in said casing adapted by its movements to control said port, a tubular liner in the interior of said valve, and means supporting 40 said liner whereby it may be adjusted within the valve to bring its axis into substantial coincidence with the axis of the valve.
7. In an internal combustion engine, the combination of a cylinder, a valve casing 45 adjacent thereto and having a port adapted to communicate therewith, a sliding sleeve valve in said casing adapted by its movements to control said port, a tubular liner in the interior of said valve, said liner being provided with a partition or abutment, 50 and means adjustably supporting said liner.
8. In an internal combustion engine, the combination of a cylinder, a valve casing 55 adjacent thereto and having a port adapted to communicate therewith, a sliding sleeve valve in said casing adapted by its movements to control said port, a tubular liner in the interior of said valve, an arm extending from one end of said liner, and a sup- 60 port whereon said arm is pivoted.
9. In an internal combustion engine, the combination of a cylinder, a pair of valve casings extending substantially parallel with each other and having ports adapted to communicate with the cylinders, a sliding sleeve 65 valve within each casing, a tubular liner in each valve, each of said liners having an arm projecting from an end thereof, and a pin whereon said arms are pivoted.
10. In an internal combustion engine, the 70 combination of a plurality of cylinders, a valve casing adjacent to each cylinder having a port adapted to communicate therewith, a sliding sleeve valve reciprocably mounted within said casing, a shaft for reciprocating said valves, a chamber for said shaft, a tubular liner within each valve sleeve, and means within said chamber for anchoring said liners.
11. In an internal combustion engine, the 75 combination of a plurality of cylinders, a valve casing adjacent each cylinder and having a port adapted to communicate therewith, a sliding sleeve reciprocably mounted within each of said casings, a shaft 80 for reciprocating said valves, a chamber for said shaft, a tubular liner for each valve having a partition or abutment extending thereacross, and means for securing said 85 liners to said chamber.
12. In an internal combustion engine, the combination of a cylinder, a valve casing having a port adapted to communicate with the said cylinder, a sliding sleeve valve reciprocably mounted within said casing and 90 adapted by its movements to control said port, an abutment in said valve at one side of the port in said casing, and a pivotal support for said abutment.
13. In an internal combustion engine, the 95 combination of a cylinder, a valve casing having a port adapted to communicate with the said cylinder, a sliding sleeve valve reciprocably mounted within said casing and 100 adapted by its movements to control said port, an abutment in said valve at one side of the port in said casing, and means sup- 105 porting said abutment whereby it may be adjusted within the valve to bring its axis into substantial coincidence with the axis 110 of the valve.
14. In an internal combustion engine, the combination of a cylinder, a valve casing having a port adapted to communicate with the cylinder, a sliding sleeve valve reciprocably mounted in said casing and adapted 115 by its movements to control said port, a tubular liner within said valve and having an abutment or partition extending there- 120 across, and a pivotal support for said liner.

In testimony whereof, I hereunto affix my signature, in the presence of two witnesses.
